UNITED STATES PATENT OFFICE.

JOHN H. HANSON, OF OAKLAND, NEBRASKA.

STOCK-WATERING APPARATUS.

SPECIFICATION forming part of Letters Patent No. 661,980, dated November 20, 1900.

Application filed March 23, 1900. Serial No. 9,893. (No model.)

To all whom it may concern:

Be it known that I, JOHN H. HANSON, a citizen of the United States, residing at Oakland, in the county of Burt and State of Nebraska, have invented certain new and useful Improvements in Stock-Watering Apparatus; and I do hereby declare the following to be a full, clear, and exact description of the invention, such as will enable others skilled in the art to which it appertains to make and use the same.

My present invention relates to certain new and useful improvements in stock-watering apparatus, and particularly to an improved construction of drinking-trough provided with readily-accessible and easily-operated means for draining and cleaning the same.

Briefly and generally stated the invention comprises a drinking-trough having a valve-controlled outlet-opening in the bottom thereof, and means for locking said valve in its open and closed positions combined with a valve-controlled inlet-pipe and means for locking said last-named valve in its open and closed positions.

In order that my invention may be fully understood, I will proceed to describe the same in detail, reference being had for this purpose to the accompanying drawings, wherein—

Figure 1 is a sectional view of a drinking-trough constructed in accordance with this invention. Fig. 2 is a plan view of the same. Fig. 3 is a detail perspective view of the guard or shield for the valve-operating means in the trough. Figs. 4 and 5 are detail perspective views of a modified arrangement of locking means for the valve-operating levers.

Referring to the drawings, the reference-numeral 1 indicates a water-chamber, such as illustrated and described in my application for patent, Serial No. 741,090, filed December 21, 1899, which is supplied with water by means of a pipe 2, leading from any suitable source of supply, and the numeral 3 indicates my improved trough communicating with the water-chamber by means of a pipe 4, the height of the water in said trough being controlled by a valve 5, to the stem 6 of which is attached a float 7. The water-chamber, valve, and float are the same as the

corresponding parts shown in my said application, above referred to, and need not therefore be specifically described herein; but while I have shown my present improvements 55 in connection with a particular form of water-controlling means I desire to have it understood that I reserve the right to use my improved drinking-trough in connection with any form of water-supply and regulating 60 means.

Within the water-chamber 1 is a swinging valve 8, hinged at its upper end to suitable ears, as shown, said valve being arranged to open and close communication with the pipe 65 4 by means of a rod 9 passing through the said pipe, the opposite end of said rod being attached to an operating-lever 10, which is pivoted to ears or lugs 11 in the bottom of the trough 3. Extending transversely across 70 the upper central part of the trough is a flanged cross-bar 12, having two pairs of notches 13 13' and 14 14' cut or formed therein, the notches 13 13' forming seats or rests for the upper end of the lever 10, whereby the 75 latter may be held in a fixed position to hold the valve 8 either open or closed. As shown in Fig. 1, the lever 10 is seated in the notch 13, and when in this position the valve 8 is held open, so that water may flow from the 80 water-chamber 1 into the trough. If it is desired to shut off the flow of water to the trough, the lever 10 will be shifted so that its upper end will lie in the notch 13', and this will draw the valve 8 to its seat, thus 85 closing the mouth of the pipe 4, as will be readily understood.

In order to drain the trough for cleaning purposes or to prevent the water from freezing therein, I provide an outlet-opening 15 90 in the bottom 16 thereof, said opening being controlled by means of a valve 17, which is operated or moved to and from its seat by a lever 18, securely attached to the upper face of the valve. The upper end of the lever 18 95 is held so as to retain the valve either open or closed by engaging either of the notches 14 14' in the cross-bar 12. In the position shown in Fig. 1 the upper end of the lever 18 is seated in the notch 14, in which position 100 the valve is held closed. By releasing the lever from the notch 14 and shifting it so that

it will engage the notch 14' the valve will be lifted from its seat and held in this position, so as to drain the trough.

In order to prevent the levers and valve located within the trough from being tampered with or accidentally disarranged, I have provided a guard or protector comprising a top plate 19, having side wings 20, which lie upon opposite sides of said levers, the said top plate being hinged at its rear end, at the points 21, to the back of the trough, and at the front said plate is provided with a suitable spring or other catch 22, engaging a keeper 23 on the trough to retain the guard or protector in position.

In practice I prefer to form the levers 10 and 18 of spring metal, so that they will have a yielding action, which will insure a tight closure of the valves and render the levers more easy of operation.

In Figs. 4 and 5 I have shown a slightly-modified arrangement of locking means for the valve-operating levers, and in most cases I prefer to employ this said means. In the views last referred to the trough 3 is provided across the upper central part thereof with a cross-bar 24, provided with two pairs of notches 25, and to one face or side of said bar is attached two metal clips 26, each consisting of a single strip of spring metal having its opposite ends 27 bent laterally and extended through the notches 25 in the cross-bar to provide supporting-shoulders for the levers 10 and 18. The metal clips 26 are attached intermediate their ends to the cross-bar and the free portions 28 of said clips are bent outward on an incline, so that they normally stand away from the cross-bar, as shown, and thus act as supports for the levers. In operation one of the free portions 28 of a clip is pressed inward, so that it will lie flush or flat with the cross-bar, and the lever being then free to be moved it may be caused to ride over the opposite free portion of the clip, forcing the same inward against the cross-bar until the lever passes over the end thereof, whereupon said end will snap or fly back to its normal position, and thus form a shoulder against which the lever rests to hold or lock the latter against movement. The clips 26 being of spring metal they will automatically assume the position shown in the drawings and be retained in such position by the springy nature of the metal employed.

By the arrangement shown and described it will be seen that I have provided simple and easily-operated means for cutting off or admitting the flow of water to the trough and for draining the latter for cleaning or other purposes. The several parts of the apparatus are of simple construction and the arrangement is such that they are not likely to get out of order.

I do not wish to be understood as limiting myself to the precise construction of valves shown, for it will be obvious that other types

may be employed without departing from the spirit of the invention.

What I claim, and desire to secure by Letters Patent, is—

1. In a stock-watering apparatus, a drinking-trough having an outlet-opening in its bottom, and a valve therefor, a water-inlet pipe leading to the trough, a valve controlling the flow of water through said pipe, resilient levers for operating said valves, and means with which said levers engage for retaining them in position to hold the valves open or closed, substantially as described. 70

2. In a stock-watering apparatus, the combination with the drinking-trough having an outlet-opening in its bottom and a valve therefor, of a water-inlet pipe for the trough, a valve controlling the flow of water through said pipe, and means for locking said valves 85 in their open and closed positions.

3. In a stock-watering apparatus, the combination with the drinking-trough having an outlet-opening therein, and a valve therefor, of a water-inlet pipe for the trough, a valve 90 controlling the flow of water through said pipe, independent levers for operating said valves, and means with which said levers engage for locking them in position to hold the valves open or closed. 95

4. In a stock-watering apparatus, the combination with the drinking-trough having an outlet-opening in its bottom and a valve therefor, of a water-inlet pipe leading into the trough, a valve controlling the flow of water 100 through said pipe, independent levers located within the trough for operating said valves, and a notched bar having spring-clips attached thereto with which said levers engage for locking them in position to hold the valves 105 open or closed.

5. In a stock-watering apparatus, the combination with the drinking-trough having an outlet-opening in its bottom and a valve therefor, of a water-inlet pipe leading into the 110 trough, a valve controlling the flow of water through said pipe, independent levers located within the trough for operating said valves, a notched cross-bar secured within the trough and having spring-clips attached thereto with 115 which said levers engage for the purpose specified, and a protector-plate hinged to the trough and provided with side wings which inclose the levers and cross-bar, substantially as described. 120

6. In a stock-watering apparatus, the combination with the drinking-trough, of a water-chamber, a float-valve in the chamber for controlling the water-level in the trough, a pipe leading from said trough to the water-chamber, a valve for controlling the flow of water through said pipe, and means for holding said valve in its open and closed positions, substantially as described. 125

7. In a stock-watering apparatus, the combination with the drinking-trough having a valve-controlled outlet in its bottom, of a wa- 130

- ter-chamber, a pipe leading from said trough to the water-chamber, a valve in the water-chamber controlling the flow of water through said pipe, a pivoted operating-lever for said valve located within the trough, a connection between said lever and valve, a cross-bar arranged within the trough, and engaging means for the lever carried by said cross-bar, substantially as described. 5 25
- 1c 8. In a stock-watering apparatus, the combination with the trough having a valve-controlled outlet in its bottom, of a water-chamber, a pipe leading from said trough to the water-chamber, a valve in the water-chamber controlling the flow of water through the pipe, a pivoted operating-lever for said valve, located within the trough, a connection between said valve and lever, and means for locking said lever in position to hold the valve 15 open or closed. 30
- 15 9. In a stock-watering apparatus, the combination with the drinking-trough having a valve-controlled outlet-opening in its bottom, of a water-chamber, a pipe connection between the trough and chamber, a float-valve regulating the flow of water to the chamber, a valve controlling the flow of water from the chamber to the trough, and means located within the trough for operating the said last-named valve, substantially as described. 35
- 2c 10. In a stock-watering apparatus, the combination with the drinking-trough, of a water-supply pipe therefor, a valve controlling the supply of water passing through said pipe, an operating-lever for said valve, pivoted within the trough, a rod passing through said pipe and attached at one end to the lever and at its opposite end to the valve, and means for locking said operating-lever in the open or closed position, substantially as described. 40

In testimony whereof I affix my signature in presence of two witnesses.

JOHN H. HANSON.
